PLATEN ROLL SHAFT FOR A TYPEWRITING MACHINE

John E. Schaefer, Chicago, Ill., assignor to United Autographic Register Co., a corporation of Illinois

Application March 16, 1940, Serial No. 324,431

4 Claims. (Cl. 197—145)

This invention relates to typewriting machines, and more particularly to an improved supporting and driving shaft for a platen roll which will facilitate removal and replacement of the platen roll.

It has been found that in order to get proper typing legibility, it is desirable to be able to use either a hard or a soft rubber platen, depending on how many copies are to be made. Heretofore, it has been extremely difficult to remove the platen roll of a typewriting machine, such as a tabulating machine, and to make the change usually required the help of a competent mechanic. One of the objects of the present invention is to provide a shaft that will enable the platen roll to be changed, as desired, by the regular operator of the machine.

The invention is illustrated in a preferred embodiment in the accompanying drawings, in which—

Figure 1 is a broken front elevational view of a tabulating machine embodying the invention; Figure 2, a broken elevational view, on an enlarged scale, showing the platen roll and supporting shaft removed from the machine; Figure 3, a sectional view, taken as indicated at line 3 of Figure 2; Figure 4, a view of the clamping section on the supporting shaft with the shaft turned 90° from the view shown in Figure 2; and Figure 5, a sectional view, taken as indicated at line 5 of Figure 2.

In the embodiment illustrated, the invention is shown applied to a tabulating machine of well known construction. The machine has a pair of side frames 6 and 7 in which the platen roll supporting shaft is journaled. The shaft is made up of two sections, the section 8 being journaled in the side frame 7 and the withdrawable section 9 being normally journaled in the side frame 6.

As best shown in Figures 1, 2, and 4, the short section of the shaft has a journal portion 10 and is provided at its outer end 11 with a trunnion which carries ratchet gears 12 which are driven through a suitable drive mechanism 13 by an electric motor 14. The inner portion of the shaft has an integrally formed bifurcated clamping block 15 which affords a socket 16 to receive the inner end of the withdrawable section of the shaft. The block is drilled and tapped to receive machine screws 17 which may be provided with socket heads 17a to enable the device to clamp the withdrawable section firmly in the position shown in Figure 2.

The withdrawable section in the shaft has its

inner end with slightly reduced diameter to fit into the socket member. The other end of the shaft extends to an outer knob 18 of small diameter which makes a driving connection with a large knob 19 through a planetary gear (not shown). The knob 19 is provided with a sleeve 20 which is journaled on the shaft 9 and has a number of slots 21 which are adapted to make a splined connection with the end gear 22 of the platen roll 23. The planetary gear arrangement between the knobs 18 and 19 enables the platen roll 23 to be rotated adjustably with respect to the shaft 9, but no invention is claimed in this application in connection with that part of the device.

The tabulating machine is shown provided with a continuous-form feeding device 24 which is driven by the gear 22 through driving gears 25. This feed mechanism is shown and described in Jensen Patent No. 2,130,015, issued September 13, 1938.

When it is desired to change the platen roll in a machine equipped with the present invention, it is merely necessary to remove the stationery from around the platen, loosen the screws 17, and pull the shaft 9 clear out through the side frame 6. The platen roll may then be lifted out of its carriage and another roll placed in its position. The shaft may then be projected through the frame 6 and the hollow platen roll until the end portion is received by the socket member 15. Upon tightening of the screws 17 the machine is again ready to operate.

It will be understood that the section 8 of the shaft is not disturbed in changing the platen roll. When the section 8 has been inserted through the platen roll and engaged by the clamping member 15, the platen roll 23 is secured against lateral shifting by having its left end, as viewed in Figure 2, abutting against the member 15 and its right end is held by the sleeve 20. Thus the gear 22 is properly aligned with the gears 25 and the platen is firmly held in position.

The foregoing detailed description has been given for clearness of understanding only, and no unnecessary limitations should be understood therefrom for some modifications will be obvious to those skilled in the art.

I claim:

1. In a typewriting machine having a pair of side frames and a rotatable hollow platen roll between said frames, means for driving and supporting the platen roll, comprising: a driven stub shaft journaled in one side frame and provided at one end with a gripping device between said

side frames; and a withdrawable shaft adapted to impale the platen roll and having its end engaged and supported by said gripping device, said withdrawable shaft having a driving connection with said platen roll.

2. A device as specified in claim 1, in which the gripping device comprises a bifurcated block formed integrally with the stub shaft and affording an axially disposed socket to receive the 10 end of the withdrawable shaft, said block having screw-members for adjustably clamping said shaft.

3. A drive shaft for a hollow platen roll of a typewriting machine having a pair of side frames, 15 comprising: a shaft section adapted to be journaled in one of the side frames of the typewrit-

ing machine, said section having at its outer end a driving gear and at its inner end, between said side frames, a bifurcated clamping socket member equipped with clamping screws; and a withdrawable shaft section adapted to be projected through and journaled in an opposite side frame of said typewriting machine, the inner end of said withdrawable section being formed to fit into said clamping socket, and said shaft having a driving connection for the platen roll.

4. A drive shaft as specified in claim 3, in which the socket member forms an abutment to limit axial movement of a platen roll in one direction and the withdrawable section has a sleeve to limit axial movement in the opposite direction.

JOHN E. SCHAEFER.
